UNITED STATES PATENT OFFICE

JOSEPH W. GOSLING, OF SCHENECTADY, NEW YORK, ASSIGNOR TO GENERAL ELECTRIC COMPANY, A CORPORATION OF NEW YORK

DESIGN FOR A LAMP GLOBE

Application filed June 20, 1930. Serial No. 36,111. Term of patent 14 years.

To all whom it may concern:

Be it known that I, JOSEPH W. GOSLING, a citizen of the United States, residing at Schenectady, in the county of Schenectady, State of New York, have invented a new, original, and ornamental Design for a Lamp Globe, of which the following is a specification, reference being had to the accompanying drawing.

Fig. 1 is a rear view in elevation of a lamp globe of my design.

Fig. 2 is a side view of the same globe. What I claim is:

The ornamental design for a lamp globe as shown.

In witness whereof, I have hereunto set my hand this 19th day of June, 1930.

JOSEPH W. GOSLING.
